(57) **CLAIM**

The ornamental design for a fly trap, as shown and described.

DESCRIPTION

FIG. 1 is a top perspective view of a fly trap, showing my new design;

FIG. 2 is a bottom perspective view thereof;

FIG. 3 is its split state diagram;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken line showing of (portions of the design) is included for the purpose of illustrating (only) and forms no part of the claimed design.
